UNITED STATES PATENT OFFICE.

WARREN KILBORN, OF SCOTTS MILLS, OREGON.

STUMP-PULLER.

1,159,953.

Specification of Letters Patent.

Patented Nov. 9, 1915.

Application filed October 31, 1914. Serial No. 269,652.

To all whom it may concern:

Be it known that I, WARREN KILBORN, a citizen of the United States, residing at Scotts Mills, in the county of Marion and 5 State of Oregon, have invented new and useful Improvements in Stump-Pullers, of which the following is a specification.

This invention relates to stump pullers, and it has particular reference to that class 10 of stump pullers wherein winding drums having ratchet wheels connected therewith are driven by pawls actuated by levers for the purpose of developing power.

The present invention has for its object 15 to provide an improved construction whereby a winding drum is provided with a plurality of ratchet wheels or rims, any one of which may be engaged by a pawl connected with a lever, said pawl being adapted to be 20 situated at various distances from the fulcrum of the lever, thus enabling the proportionate amount of power and speed to be regulated by simply adjusting the pawl to various positions on the lever.

25 A further object of the invention is to simplify and improve the general construction and operation of the machine.

With these and other ends in view which 30 will readily appear as the nature of the invention is better understood, the same consists in the improved construction and novel arrangement and combination of parts which will be hereinafter fully described and particularly pointed out in the claims.

35 In the accompanying drawing has been illustrated a simple and preferred form of the invention, it being, however, understood that no limitation is necessarily made to the precise structural details therein exhibited, 40 but that changes, alterations and modifications within the scope of the claims may be resorted to when desired.

In the drawing, Figure 1 is a top plan view of a machine constructed in accordance 45 with the invention. Fig. 2 is a side elevation with parts broken away. Fig. 3 is a top plan view enlarged of the operating lever and the pawls connected therewith. Fig. 4 is a sectional detail view taken on the line 50 4-4 in Fig. 3.

Corresponding parts in the several figures are denoted by like characters of reference.

The frame of the machine includes a cross bar 10 and side members 11, which latter are 55 provided with bearings for a shaft 12 on

which two winding drums 13, 13 are supported for rotation, each of said drums carrying a wheel 14. The winding drums are spaced apart by a sleeve or washer 15. Each of the wheels 14 carries a plurality of 60 ratchet rims 16, two of such rims being shown on each wheel, although more may be used when preferred.

The cross bar 10 supports a bracket 17 on which is fulcrumed a lever 18, said fulcrum 65 being preferably arranged midway between the wheels 14 which latter may be mounted on the inner or proximate ends of the winding drums, as shown in the drawings, although said wheels may be differently 70 positioned when preferred. The bracket 17 is also preferably extended downwardly and forwardly, as shown at 17' to afford an additional bearing for the shaft 12, thereby materially strengthening and reinforcing 75 the structure. Hingedly connected with the lever 18 by means of pintles 19 are plates 20, said plates being disposed in registry with the wheels 14. Pivottally connected with each hinge plate by means of a pin or 80 bolt 21 is a pawl 22 adapted to engage one of the ratchet rims 16, each of the plates 20 being provided with a plurality of perforations 23 for the passage of the pin or bolt 21 in order that by changing the position of 85 the latter, the pawl 22 may be placed in engagement with any one of the ratchet rims 16.

It will be readily seen that by changing 90 the position of the pawl 22, the distance between said pawl and the fulcrum of the lever will be varied, thereby increasing or decreasing the leverage, as the case may be. Thus, when the pawl 22 is in engagement 95 with one ratchet rim of a wheel 14, each throw of the lever will move the wheel to the extent of, say, one tooth, while when the pawl is placed in engagement with another ratchet rim each throw of the lever will move the wheel to the extent of, say, two 100 teeth. By increasing the number of ratchet rims on each wheel and the corresponding adjustment of the pawls, greater range of relative control of speed and power may be obtained. To prevent reverse rotation of 105 the winding drums, gravity check pawls 24 are provided, the same being pivoted on the side members of the frame.

A cable 25 is provided, the ends of said cable being connected with the two drums 110

13, while on the cable is guided a pulley block 26 having attaching means, such as a hook 27, which may be connected in any convenient way with the stump that is to be extracted. It will be seen that by rocking the lever 18 the drums 13 will be alternately actuated to wind thereon the cable 25, thereby producing the requisite power to extract the stump. The frame structure of the machine may be mounted on runners, as seen at 28, for convenience in moving from place to place.

Having thus described the invention, what is claimed as new, is:—

- 15 1. A winding drum supported for rotation, a plurality of ratchet rims on said drum, a lever fulcrumed adjacent to the drum, a plate hingedly connected with the lever, and a pawl connected pivotally and adjustably with the plate to engage any one of the ratchet rims.
- 20 2. A frame including side members, a

cross bar and a bracket having a downward and forward extension, a shaft supported for rotation in the side members and having an additional bearing in the extension of the bracket, winding drums supported for rotation on the shaft, one at each side of the bracket extension, each drum having a plurality of ratchet rims connected therewith, a lever fulcrumed on the bracket, pawls connected with said lever, adjustable with respect to the fulcrum thereof, one pawl adapted to engage a ratchet rim of each drum, and check pawls fulcrumed on the frame in engagement with a ratchet rim of each drum.

In testimony whereof I affix my signature in presence of two witnesses.

WARREN KILBORN.
